ELECTRICAL SIGNALING SYSTEM

Robert Raymond Birss, Harrogate, England

Application July 17, 1942, Serial No. 451,306
In Great Britain September 23, 1941

6 Claims. (Cl. 179—16)

The present invention relates to electrical signalling systems such as automatic telephone systems in which impulses are utilised to effect the positioning of selective apparatus and like operations and it is more particularly concerned with arrangements for correcting impulse distortion whereby the operating range and capabilities of such systems may be increased.

In systems where alternating current impulsing is employed distortion of the envelope of each signal impulse results due to the reactive characteristics of the line and also due to the presence of tuned filter circuits at the signal receiving point, when these are provided. The distortion usually takes the form of a delay in the change of current at the beginning and end of each impulse so that instead of possessing its original ideal rectangular form it has incremental and decremental slopes approximately characteristic of the charge and discharge of condenser through a resistance.

The invention has for its general object the provision of a simple and efficient method of correcting distorted alternating current impulses.

According to the invention alternating current signals received over a line are rectified and applied to two voltage responsive devices one of which serves to generate a voltage surge to supplement the action of the second whereby a signal responsive device controlled by the second is caused to operate rapidly.

According to the invention a distorted alternating current signal impulse is rectified and applied as a direct current voltage signal to the grid of a voltage responsive valve connected in parallel with a signal voltage responsive valve proper, there being connected in the anode circuit of the first valve the primary winding of a transformer, the arrangements being such that voltage surges are produced in the transformer secondary winding at commencement of the incremental and decremental slopes of the input signal which mark the beginning and end of the original signal impulse, these voltage surges being fed back and applied in parallel with the received signal to the grid of the signal receiving valve in such manner that they augment the received signal input to this stage and produce a resulting current signal in the anode circuit thereof having incremental and decremental slopes which are very steep.

The correcting device shown in the drawing is assumed to form the impulse receiving part of an alternating current signal receiver adapted to deliver direct current impulses to local receiving

equipment and the description will merely concern itself with this part.

The line over which alternating current signal impulses are received will in the case of a voice frequency signal receiver, connect with the signal responsive apparatus via suitable tuned filter circuits, not shown, and it will be understood that for correction purposes the signals will first be rectified and then applied as direct current voltage pulses to terminals 10 and 11 across which is connected the rectifier network load resistance R1. Terminals 10 and 11 connect via resistance R2 to the grid of the impulse receiving valve V1 in the anode circuit of which is connected the impulsing relay A, which is preferably of a high speed type. Connected in parallel with valve V1 is the valve V2 on to the grid of which a part of the input is diverted via resistance R4.

The alternating current signal impulses received over the line are essentially voltage signals and the direct current signals delivered from the rectifier arrangement preceding the arrangements shown in the drawing will therefore be ones having voltage but little current, but they each will have incremental and decremental slopes at their beginning and end similar to those of the incoming distorted alternating current signals. In order to effect correction it is necessary to steepen the incremental and decremental slopes thereof, and this is effected by the additional valve V2 and the associated transformer TR1 connected in the anode circuit thereof. The valve V2 serves as a voltage operated device adapted to produce a varying current in its anode circuit corresponding to the varying voltage input. This current in extending through transformer TR1 will cause surge voltages to be produced in the secondary winding during the transient conditions at the commencement and end of each impulse and these voltages are fed back to the signal receiving valve V1 in such manner as to assist the signal input and so steepen the slopes of the envelopes of the output signals delivered in its anode circuit.

Reviewing the circuit operations in more detail it will be understood that the grid of valve V1 is normally negatively biased with respect to its cathode by means of the automatic bias resistances R5 and R7 to a value such that the normal anode current flow is insufficient to operate or hold relay A, while the grid of valve V2 is similarly biased towards cut-off by means of the bias resistances R6 and R8.

During the rise of voltage at commencement of an applied direct current voltage impulse, that

part of the input energy which is by-passed to the grid of valve V2 will gradually reduce the standing negative potential on its grid and an increasing current will flow in its anode circuit. This current in extending through the primary winding of transformer TR1 produces a surge voltage in the secondary winding which is fed back and applied in parallel with the received signal to the grid of valve V1 in such fashion as to augment the effect of the received signal on this stage. The effect of the received signal on valve V1 is at its commencement to reduce the negative bias on the grid and so increase the anode current to a value such that relay A will operate, but the positive feedback from transformer TR1 has the effect of increasing the rate of change of grid voltage and so steepens the initial rising slope of the wave form of the anode current flow.

At termination of the impulse, when the grid of valve V1 commences gradually to return to its standing negative value and so releases relay A, the positive feedback circuit comes into operation to increase the rate of restoration of the standing grid voltage of valve V1.

Another point which arises in connection with the positive feedback circuit from transformer TR1 is that the feedback voltage in addition to being applied to the grid of valve V1 also finds a circuit on to the grid of valve V2. The value of the feedback to valve V2 will be kept below that at which oscillation occurs by selection of the resistance values R1, R2 and R3 which together form a potential divider circuit giving an applied voltage of

$$\frac{E \times R1}{R1 + R2 + R3}$$

where E is the output voltage in the secondary winding of transformer TR1, and it will be understood that in result the slopes of the signal delivered in the anode circuit of valve V1 are still further steepened.

Similar considerations apply for subsequent received impulses, the resulting output impulses in the anode circuit of valve V1 becoming ones having incremental and decremental slopes which are extremely steep and the output signals delivered by armature a_1 of relay A on to leads 16 and 17 therefore tend to approximate closely to an ideal rectangular form.

In the manner thus described the invention enables correction of envelope distortion of alternating current impulses to be effected, and in cases where filter networks are employed at a receiving point it enables these to be of high selectivity types, the use of which has been hitherto not too desirable due to the envelope distortion effect they tended to produce.

The invention is moreover not limited to any particular method of alternating current impulsive, as the impulses may comprise a low frequency or high frequency alternating current transmitted either directly or as modulations on a carrier wave. The invention is furthermore applicable to alternating current impulse repeating arrangements as well as to receivers.

In cases where the received signal is so distorted that the desired correction cannot be achieved in one stage it is possible that advantage may be gained by using a two-stage correction arrangement in which the partially corrected signal would be passed from a first stage through a second stage before being extended to the output circuit.

It will be appreciated that the invention is not limited solely to alternating current impulses but rather to any direct current impulses having substantial voltage changes with little or no current as occurs in the case of the rectified output from tuned circuits to which alternating current signals are applied.

A second stage correction could conveniently be effected by the correcting device described in my co-pending application Ser. No. 451,305, filed July 17, 1942.

I claim:

1. In a signaling system, a signaling circuit upon which rectified alternating current signals are impressed at times, a pair of voltage responsive devices each having an input circuit and an output circuit, means coupling the input circuits of both devices to said signaling circuit, whereby said devices are effective to energize their respective output circuits responsive to a rectified alternating current signal being impressed upon said signaling circuit, a transformer having a winding connected in the output circuit of one of said devices, and means connecting another winding of said transformer to the input circuit of the other of said devices, whereby the energization of said one device's output circuit causes a voltage surge to be generated in said other device's input circuit and therefore enhances the energization of said other device's output circuit.

2. In a signaling system, a pair of electronic valves each having a grid and a plate circuit, a common signal input to which the grids of both valves are coupled, a responding device in the plate circuit of one of said valves, means for impressing a direct current voltage upon said input thereby to cause said one valve to operate said device, and a transformer having one winding connected in the plate circuit of the other of said valves and a second winding connected to the grid of said one valve, thereby to increase the speed with which said one valve operates said device responsive to said voltage being impressed upon said input.

3. In a signaling system, a pair of electronic valves each having a grid and a plate circuit, a common signal input to which the grids of both valves are coupled, a responding device in the plate circuit of one of said valves, means for impressing a direct current voltage upon said input thereby to cause said one valve to operate said device, and an inductive link between the plate circuit of the other of said valves and the grid of said one valve thereby to provide a positive feedback to said one valve for increasing the speed with which said one valve operates said device responsive to said voltage being impressed upon said input.

4. In a signaling system, a pair of electronic valves each having a grid and a plate circuit, a common signal input to which the grids of both valves are coupled, a responding device in the plate circuit of one of said valves, means for impressing a direct current voltage upon said input thereby to cause said one valve to operate said device, an inductive link between the plate circuit of the other of said valves and said common input thereby to provide a positive feedback to said one valve for increasing the speed with which said one valve operates said device responsive to said voltage being impressed upon said input, and means for preventing said inductive link from causing said other valve to oscillate.

5. In a signaling system, a signaling circuit upon which rectified alternating current signals

are impressed at times, a pair of voltage responsive devices each having an input circuit and an output circuit, means coupling the input circuits of both devices to said signaling circuit, whereby said devices are effective to energize their respective output circuits responsive to a rectified alternating current signal being impressed upon said signaling circuit, and means for inductively coupling the output circuit of one of said devices to the input circuit of the other of said devices thereby to quicken the energization and de-energization of said other device's output circuit.

6. In a signaling system, a pair of electronic

5 valves each having a grid and a plate circuit, a common input to which the grids of both valves are coupled, a responding device in the plate circuit of one of said valves, means for impressing a direct current voltage upon said input thereby to cause said one valve to operate said responding device, a positive feedback in the form of an inductive link between the plate circuit of the other of said valves and the grid of said one valve, thereby to produce a current signal to said responding device having incremental and decremental slopes which are very steep.

ROBERT RAYMOND BIRSS.
